UNITED STATES PATENT OFFICE.

EDWIN FERGESSON STEWART, OF WOODCLIFF, NEW JERSEY, ASSIGNOR OF ONE-HALF
TO THE BARRETT COMPANY, A CORPORATION OF NEW YORK.

LIQUID OR GASEOUS FUEL BURNER.

1,231,447.

Specification of Letters Patent. Patented June 26, 1917.

Application filed October 12, 1916. Serial No. 125,256.

To all whom it may concern:

Be it known that I, EDWIN F. STEWART, a citizen of the United States, residing at Woodcliff, in the county of Hudson and State of New Jersey, have invented certain new and useful Improvements in Liquid or Gaseous Fuel Burners; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in liquid fuel burners and the object in view is to produce a new feature not found in burners commonly in use and adapted to secure a continuous and uninterrupted service and eliminate the very fine screening of the fuel or tar and, at the same time, lessening the cost of labor in attention and supervision of the furnace in connection with which the burner is used.

Heretofore the cost of petroleum fuel has increased appreciably, a fact which has brought coal tar and oil tar into the field as a fuel substitute for the petroleum oils. The heavier tars are, of course, more viscous and are apt to carry more sediment and solid matter than the usual grades of fuel oil or crude petroleum. A burner which will handle petroleum fuel successfully will not always give equally good results with coal tar, while with oil tar less trouble is experienced, due to its viscosity and incidentally it is a petroleum by-product from the manufacture of water gas.

It is quite the usual practice to screen or filter petroleum and tar fuels after their temperature has been raised to a point which will make them sufficiently fluid or of such viscosity that they will screen or filter readily; the degree of heating being contingent upon the viscosity of any given fuel at normal temperature and may range anywhere between 75 degrees for light petroleum and oil tar to 650 degrees for heavy or hard petroleum, coal tars, residues and pitches.

To maintain the usual flow of fuel oil, oil tar or coal tar under fifty to a hundred pounds pressure at the nozzle or burner, even through a $\frac{1}{4}$ or $\frac{3}{8}$ needle valve, the plug needs to be lifted only a very slight distance from the seat, which leaves a very thin annular

space through which the liquid may flow, so that very small particles of sediment or solid matter readily find lodgment in this crevice and gradually build up so that possibly the flow is, after a time, cut off entirely, thus making it necessary to open and close the valve two or three times to free the annular opening of sediment, after which the valve must again be adjusted to maintain the original and desired flow of fuel. It has been demonstrated that this is one of the greatest troubles with previous types of burners as constant attention is required to maintain a uniform and continuous fire.

To obviate these objections, I employ a compartment casing, one compartment adapted to contain fuel and the other air or steam, and the provision of a fuel tube having communication with the fuel chamber and rotatable, perforated elements for controlling the feeding of the fuel in connection with adjustable means for directing steam or air tangentially to the stream of fuel.

The invention consists of various other details of construction, combinations and arrangements of parts which will be herein-after fully described, shown in the accompanying drawings and then specifically defined in the appended claims.

My invention is illustrated in the accompanying drawings, in which:

Figure 1 is a side elevation of a burner made in accordance with my invention.

Fig. 2 is a sectional view on line 2—2 of Fig. 1.

Fig. 3 is an end view of the burner.

Fig. 4 is a sectional view on line 4—4 of Fig. 3.

Fig. 5 is a sectional view on line 5—5 of Fig. 2.

Fig. 6 is a sectional view on line 6—6 of Fig. 2.

Fig. 7 is a detail view in elevation of the graduated dial plate.

Fig. 8 is a detail view of the invention.

Fig. 9 is a plan view of the orifice plate.

Figs. 10 and 11 are detail views showing the nozzles arranged so as to direct sprays of steam tangentially against a jet of fuel merging from the central tube.

Reference now being had to the details of the drawings by numeral, 1 designates a fuel burner of iron or composition casting, divided internally into two compartments, designated by numerals 2 and 3, the former of which is adapted to receive liquid fuel

fed thereto through a pipe 4, shown in dotted lines in Fig. 2 of the drawings, while the chamber 3 is designed to receive the atomizing agent, such as steam or air under pressure, and which is conveyed thereto in any suitable manner through the opening 5. Said chamber 2, which is generally cylindrical in form, has its inner end closed by a perforated disk 6, a detail of which is shown in Fig. 9 of the drawings, and which is provided with perforations 7 of different diameters for the purpose of allowing different quantities of fuel to be fed to the burner. The outer end of the chamber is flanged as at 8 and has secured thereto a plate 9, held by bolts 10 upon which nuts 11 are fitted, and fastened to the outer face of the plate 9 is a dial plate 12, a face view of which is shown in Fig. 7 of the drawings, and upon which are numbers designating the diameters of the different apertures in the disk 6. A valve stem 13 is mounted in an aperture in the boss 14 projecting from the inner face of the plate 9 and also in a gland 15 fitted in a threaded aperture in the plate 9. The inner end of the valve stem 13 is contracted as at 16 and has a bearing in the wall intermediate the two chambers 2 and 3. It will be noted that the plate 6 is held upon the stem by means of the flanged collar 17 which is secured to the perforated disk through the medium of the rivets 18. A coiled spring 19 bears intermediate the disk 6 and a collar 18*, which is part of the stem 13, and tends to normally hold the disk against an annular boss 20 formed in the inner end of the wall of the chamber 2 and through which boss a duct 21 leads. A flat corrugated spring 35 is so mounted with relation to the stem and orifice disk as to brush lightly over the front face of the orifice plate when the stem is rotated for the purpose of cleaning off any accumulation of foreign matter that might lodge over one of the orifices. An index finger 22 is fixed to the stem 13 and is adapted to move adjacent to the face of the dial, to designate the different relative positions of the perforated disk 6, and a handle 23, fixed to the outer end of the stem 13, serves as a means for rotating said stem.

A pipe 24 has threaded connection with the walls of a socket 25 formed in the forward end of the valve casing, and 26 is a tube threaded into the outer end of the pipe 24 and held in different relative adjusted positions therein through the medium of the jam nut 27. A sleeve 28 is mounted upon the pipe 24, being held in different positions thereon through the medium of the set screw 40 mounted in a threaded aperture in a flange 28*, and its outer end is provided with a flange 29 having elongated slots 30 therein through which the tubes 31 pass, which latter are held in apertures leading through the

adjacent wall of the casing into the chamber 3 and are held therein by means of the set screws 31*. A disk 32, a detail of which is shown in Fig. 5 of the drawings, is provided with elongated slots 33* formed at right angles to the slots 30, shown in solid and dotted lines in Fig. 5 of the drawings, and through which slots the pipes 31 pass. At the outer end of each of the pipes 31, a contracted and angled shape nozzle 33 is fixed with its free end positioned adjacent to the end of the nozzle tube 26. The collar 32 is positioned close to and in contact with the flange 29 and it will be noted that the two series of elongated or oblong holes in the collar 32 and the flange register and that the sides of the oblong holes in the collar and flange are adapted to have sliding contact with the pipes 31, thus providing means whereby the tubes 31 may be warped slightly in order to throw the nozzle ends into the different tangential positions shown in Figs. 10 and 11 relative to the central pipe 26.

In operation, when starting the burners, air or steam is introduced into the chamber 3 through the opening 5, the valves controlling the supply being sufficient to give approximately the required volume of the atomizing agent desired, after which the supply of liquid fuel or gas is introduced through the pipe 4 into the compartment 2, the indicating pointer 22 first having been positioned midway between the figures denoting the largest and smallest openings in the perforated disk 6. After the fuel has been admitted into the chamber 2, the stem 13 is rotated slightly so that the indicating pointer 22 will register with the opening corresponding to the smallest number on the indicating pointer, bringing the minimum or smallest orifice into complete registration with the duct or opening 21 and which will supply to the nozzle the minimum amount of fuel under pressures and temperatures that exist. There will now be a small stream of oil or other liquid fuel flowing to the delivery end of the fuel tube 26 and entering the zone of impact from the four converging nozzles 33. Each opposite pair of the nozzles will deliver its jets diagonally across the issuing stream of oil and in opposition to each other with a force or impact peculiarly adapted to the work of disintegrating or breaking up the stream of liquid fuel into a spray of very fine particles or into a vaporous form or state. This operation will produce a cloud of oil vapor mixed with the atomizing agent and such combustion air as may be supplied either through the pipe 31 or from an opening in the furnace wall around the burner or from both sources and in general the result is an inflammable mixture that will readily ignite to form an intense heat and in this way deliver heat to the furnace.

When the opposed pairs of nozzles 33 are diametrically opposite to each other with reference to the center or axis of the oil delivering tube 26, the oil breaks up into a cloud of spray, moving into no particular direction excepting into the furnace and toward the stack but, when the sleeve 28 is rotated slightly in either direction, the positions of the nozzles 33 will be slightly changed with reference to the center of the oil tube 26, causing the converging jets of air to act tangentially upon the stream of fuel, thus giving a whirling effect to the latter and producing a cloud of mixed fuel and air in whatever direction desired. It has been found that this whirling effect has a decided advantage under certain conditions of furnace construction and over certain classes of heating surface. It will be noted that either form of flame may be produced at will by the operator without shutting off the fuel or atomizing agent to make changes in the burner.

After the fire is started by first admitting fuel through the minimum size orifice, its intensity may afterward be increased by rotating the valve stem until the size of the orifice, which gives the desired volume of furnace heat and temperature, is shown directly at the indicator.

By the provision of the flat corrugated spring 35, arranged as shown, the same will brush lightly over the front face of the orifice plate when the stem is rotated to clean off any accumulation of foreign matter that might lodge over one or another of the orifices.

What I claim to be new is:—

1. A liquid or gaseous fuel burner, comprising a casing with two compartments, one adapted to contain fuel and the other steam or air, a fuel tube mounted in said casing and having communication through a duct with the fuel chamber, a rotatable perforated disk for controlling the fuel fed through said duct, tubes communicating with the steam or air compartment, nozzles upon the tubes, and means for actuating the tubes to cause the nozzles to assume tangential positions relative to the exit end of the fuel tube.

2. A liquid or gaseous fuel burner comprising a casing with two compartments, one adapted to contain fuel and the other steam or air, a fuel tube mounted in said casing and having communication through a duct with the fuel chamber, a rotatable perforated disk for controlling the fuel fed through said duct, tubes communicating with the steam or air compartment, nozzles upon the tubes, and an adjustable sleeve adapted to engage the tubes to be positioned in different tangential positions relative to the exit end of the fuel pipe.

3. A liquid or gaseous fuel burner com-

prising a casing with two compartments, one adapted to contain fuel and the other steam or air, a fuel tube mounted in said casing and having communication through a duct with the fuel chamber, a rotatable perforated disk for controlling the fuel fed through said duct, tubes communicating with the steam compartment, nozzles upon the tubes, a sleeve journaled upon said pipe and provided with a flanged portion with slots therein through which said tubes pass, angled nozzles upon the tubes, said tubes being actuated by a rotary movement of the sleeve to cause the exit ends of the nozzles to be held in different positions tangential to the exit end of the oil tube.

4. A liquid or gaseous fuel burner comprising a casing with two compartments, one adapted to contain fuel and the other steam or air, a fuel tube mounted in said casing and having communication through a duct with the fuel chamber, a rotatable perforated disk for controlling the fuel fed through said duct, tubes communicating with the steam compartment, a sleeve journaled upon said pipe and provided with a flanged portion with slots therein through which said tubes pass, angled nozzles upon the tubes, said tubes being actuated by a rotary movement of the sleeve to cause the exit ends of the nozzles to be held in different positions tangential to the exit end of the oil or fuel tube, and means for holding the sleeve in different adjusted positions.

5. A liquid or gaseous fuel burner comprising a casing with two compartments, one adapted to contain fuel and the other steam or air, a fuel tube mounted in said casing and having communication through a duct with the fuel chamber, a sleeve journaled upon said pipe and having a flange with a threaded aperture therein, a set screw mounted in said aperture and adapted to engage the casing, said sleeve having an apertured end with oblong slots therein, tubes communicating with the steam or air chamber and passing through said slots in the flange, a disk mounted upon the pipe and provided with oblong slots at right angles to the slots in said flange and through which the tubes pass, nozzles upon the tubes and adapted to be positioned by the adjustment of the sleeve so that their exit ends will be tangential to the exit end of the fuel pipe.

6. A liquid or gaseous fuel burner comprising a casing with two compartments, one adapted to contain fuel and the other steam or air, a fuel tube mounted in said casing and having communication through a duct with the fuel chamber, a rotatable perforated disk for controlling the fuel fed through said duct, a stem journaled in suitable bearings in the casing and upon which said disk is mounted, a spring bearing yield-

ingly against said disk, an indicating dial and a pointer fixed to said stem and movable over the face of the dial, a fuel pipe communicating with a duct leading through the wall of the casing and with said fuel chamber, a sleeve rotatably mounted upon the pipe and provided with a flanged end which is slotted, a set screw mounted in the flange of the sleeve and engaging the casing, 10 tubes passing through the slots in the flange of the sleeve and communicating with the air or steam chamber, and angled nozzles fitted to the ends of the tubes.

7. A liquid or gaseous fuel burner comprising a casing having two compartments therein, one adapted to contain fuel and the other steam or air, said fuel chamber having an annular boss projecting from one wall with an oil or fuel duct leading through said 15 boss, a fuel pipe communicating with the duct, a disk, a valve having perforations of different diameters therein, a stem in the

casing and upon the squared end of which said valve is loosely mounted, a spring bearing yieldingly against said valve, a corrugated spring carried by the cover of said fuel chamber and adapted to wipe against said valve or disk, a cover to said fuel chamber, a graduated dial upon the cover, a pointer fixed to the stem and movable adjacent to the dial, a handle for rotating the stem, a sleeve journaled upon the fuel pipe and having a flanged end which is slotted, means for holding the sleeve in adjusted positions, tubes for communication with the air or steam chamber and passing through said slots in the flange, and angled nozzles fitted to the air or steam tubes.

In testimony whereof I hereinunto affix my signature in presence of two witnesses.

EDWIN FERGUSON STEWART.
